N. E. GEE.

SPRING RIGGING.

APPLICATION FILED DEC. 7, 1921.

1,413,399.

Patented Apr. 18, 1922.

UNITED STATES PATENT OFFICE.

NORMAN E. GEE, OF ALTOONA, PENNSYLVANIA.

SPRING RIGGING.

1,413,399.

Specification of Letters Patent. Patented Apr. 18, 1922.

Application filed December 7, 1921. Serial No. 520,665.

To all whom it may concern:

Be it known that NORMAN E. GEE, a citizen of the United States, residing at Altoona, in the county of Blair and State of Pennsylvania, has invented certain new and useful improvements in Spring Rigging, of which the following is a specification.

This invention relates to locomotives and has for its primary object an improvement in the spring rigging of electric locomotives wherein the driving motors are placed ahead of the driving wheels, and it is desirable that the weight on the front truck be equalized with that on the driving wheels.

Another object of this invention is to provide means for keeping the spring gear in alignment with the equalizers which are positioned over the driving boxes and carry the weight from the locomotive frame to the driving axles.

A further object of this invention is to provide means for breaking up the equalization on one end of the locomotive such as to form a three point suspension for the weight carried by the springs, thus giving a locomotive spring rigging construction that readily adapts itself to the safe operation of locomotives at high speeds.

A still further object of this invention is to provide a common fulcrum pin for a system of cross equalizers between the means designed to carry the weight on the front truck and to transfer a part of the weight to the driving wheels and the means designed to carry the weight on the main driving wheels of the locomotive.

With these and many other objects in view the same consists in the novel construction, combination, and arrangement of parts as will be hereinafter fully pointed out, illustrated and claimed.

It will be quite readily understood by those skilled in the art to which this invention belongs that the same is quite susceptible to some structural changes and modifications without departing from the spirit or scope of the invention, but a preferred and thoroughly practical embodiment of the invention is shown in the accompanying drawings in which—

Figure 1 shows an elevational view of a locomotive running gear having the present invention applied thereto.

Figure 2 shows a cross sectional view taken on the line 3—3 of Figure 1.

Figure 3 shows a cross sectional view taken on the line 3—3 of Figure 1, and shows in addition to what is shown in Figure 2, the manner of placing the gibs in the spring hangers.

Figure 4 shows a cross sectional view taken on the line 4—4 of Figure 1 and illustrates the manner of connecting the driving box equalizers with the front truck on the opposite end of the locomotive.

Figure 5 shows a plan and elevational view of the pedestal cap used in connection with the equalizing means at either end of the locomotive.

Figure 6 is a sectional view taken on the line 4—4 of Figure 1 and shows a gib connection with the hanger.

Figure 7 is an enlarged detail side elevation of the hanger which supports the horizontal arm of the bell crank.

Similar reference numerals refer to similar parts throughout the several figures of the drawings.

In carrying out this invention no change is contemplated in the manner of arranging the equalizers over the driving boxes nor in the manner in which the helical or semi elliptical springs are arranged on the frame, but as the locomotive frame which envelopes the motors is made necessarily low with reference to the rail it becomes imperative to devise other means than the usual equalizer which passes beneath the cylinder saddle on steam locomotives, in order that the same equalization can be afforded an electric locomotive wherein the driving motors are positioned ahead of the driving wheels and back of the truck or pony wheels, and to this end a bell crank, designated by the numeral 10, having two pendent arms 11 is provided. A fulcrum 12 is provided on the frame while the horizontal member engages a plate 13 which is adapted to rest upon the front truck which is not shown in the drawings.

The lower end of the pendent arm 11 is provided with a pin connection 14 which secures a jaw 15 of a tension rod 16 to the bell crank arm. The opposite end of the tension rod 16 is provided with a movable block 18 and pin connection 17. The block 18 is made slidabile between the jaws 19 of the rod 16 when it is desired to raise or lower the engine on the spring. Cooperating with the block 18, there is a pendent arm 20, of a bell crank 21, which is adapted

to be fulcrumed on the frame 22 of the locomotive. The horizontal arm 23 of the bell crank 21 is adapted to be attached through a gib connection 24 to a hanger 25 which 5 has a pin connection 25^A with a cross equalizer 26 as shown in Figures 2 and 3 of the drawings.

The cross equalizer 26 is provided with a pin 27 which secures a cross equalizer 28 thereto. The cross equalizer 28 is carried by gib 29, adapted to be fitted in the ends of pendent hangers 30 to which is securely attached the ends 31 of driving box equalizers 32 which are carried by the driving box, not 15 shown in the drawings.

The arrangement of the spring rigging from the equalizer 32 back to the helical spring 33 is of the usual design, and presents no new features that are a part of this invention.

Equalizer 34 which is positioned above the driving box of the last driving wheel is shown as having one end thereof, attached to an helical spring 35 which rests on the 25 frame as shown in Figure 1 of the drawings.

The opposite end 36 of the equalizer 34 is provided with a hanger 37, to which is attached a pendent clevis 38, the lower end of which is adapted to engage an end 39 of the 30 bell crank arm 23 as shown in Figures 1 and 6 of the drawings.

In the adoption of this design of spring gear to a locomotive of the type it is necessary to bifurcate the end 40 of the pedestal 35 cap 41. The lower bar 42 of the frame is likewise separated to permit the passage of the bell crank arm, as shown in Figures 2, 3 and 4 of the drawings.

Having thus described my invention what

I claim and desire to be secured by Letters Patent is—

1. The combination with a locomotive spring rigging, of means for equalizing the weight carried by the front trucks with the weight carried by the main drivers, said means including a plurality of cross equalizers, each having a common pin connection.

2. The combination with a locomotive truck and spring rigging, of a plurality of equalizers positioned on either side of the locomotive and on either side of the locomotive frame, means for transferring the weight carried by the spring rigging to the driving box of the locomotive, a plurality of cross equalizers having a common pin connection, and means for transferring a portion of the weight carried by the truck to the front drivers.

3. In combination with a locomotive spring rigging, springs, equalizers, bell cranks, and spring hangers a system of cross equalization in combination with bell cranks at one end of the locomotive and a combination of bell cranks without the cross equalizers at the opposite end of the locomotive, upper and lower frame bars, a bifurcated lower bar for the frame, a frame cap one end of which is bifurcated to conform with the frame, a bell crank adapted to move within the bifurcated frame and cap and means for securing the bell crank to the frame together with means associated with the bell crank for raising and lowering the locomotive on the spring gears.

In testimony whereof he affixes his signature.

NORMAN E. GEE.
